Inventor:
Peter G. Jacobson
By G. A. Snaggatty

UNITED STATES PATENT OFFICE.

PETER G. JACOBSON, OF CHICAGO, ILLINOIS.

ELECTRIC CONDENSER.

Application filed July 23, 1924. Serial No. 727,683.

My invention relates to electric condensers whose sides are formed of metal leaves or plates, the invention having for its object an improved assembly of such leaves with the supports that carry them.

In carrying out my invention the condenser leaves are received within slots or recesses which are formed in the supports for the leaves and the metal between the slots is outwardly flared or spread to press tightly upon the leaves to hold them firmly in assembly with their supports, and to evenly space the median planes of the leaves irrespective of the variations in the thickness of the leaves that usually occurs in practice.

The invention will be more fully explained in connection with the accompanying drawing in which Fig. 1 is a view of the preferred embodiment of the invention on line 1—1 of Fig. 2; Fig. 2 is a plan view, with a mounting board or panel shown in section; Fig. 3 is a sectional detail on line 3—3 of Fig. 1; Fig. 4 is a view, on a larger scale, on line 4—4 of Fig. 3; Fig. 5 is a view on line 5—5 of Fig. 4; Fig. 6 is a perspective view illustrating a step in the process of assembly; Fig. 7 is a perspective view illustrating the completion of the step illustrated in Fig. 6; and Fig. 8 is a view, on a larger scale, on line 8—8 of Fig. 3.

The condenser illustrated includes two mounting plates 1 and 2 of insulating material which are assembled upon threaded metallic rods 3 by means of nuts 4. The plate 2 is screwed upon the mounting board 5. One of the condenser sides is composed of a group of metallic leaves or plates 6, preferably three or more, formed with aligned U-shaped recesses 7 through which the mounting rods 3 pass, there being preferably three such mounting rods. A longitudinally split metallic sleeve or tube 8 embraces each rod 3 and is formed with transverse fingers 9 upon opposite sides of the split in the sleeve, these fingers entering the spaces between the leaves. These fingers are preferably initially straight, as illustrated in Fig. 6. The slots or slots 10 between the fingers are extended into the bores of the sleeve 8 and initially somewhat loosely receive the portions

of the leaves which margin the sides of the recesses 7 therein, the spaces 10 being initially wider throughout than the thickness of the thickest leaves that are apt to be employed in the construction of the condenser. In the process of assembly each split tube or sleeve 8 is preferably initially of U-form as indicated in Fig. 6, the ends of the fingers being clinched into engagement with the corresponding rod after the sleeve has been placed upon this rod with the sides of the recesses 7 in the slots between the fingers 9, as illustrated most clearly in Figs. 5, 7 and 8.

In the clinching operation, the fingers 9 are forcefully widened longitudinally of the sleeves and preferably at their tips sufficiently to tightly engage or press upon the condenser leaves received between the fingers, the mechanism for thus widening or spreading these finger tips preferably exerting widening or spreading pressure upon all the finger tips at the same time and in a manner to make equidistant the spaces between the median planes of the condenser leaves.

The other condenser side illustrated includes leaves 11 interleaved with the leaves 6 and mounted upon a rotatable shaft 12 in order that the capacity of the condenser may be adjusted, although the invention is not to be limited to such adjustability. The shaft 12, if rotatable, may be provided with a knob 13, in front of the panel or mounting board 5.

Changes may be made without departing from my invention.

Having thus described my invention, I claim:

A spacing member for condenser plates comprising a split tube having a plurality of cross slits extending at right angles to its axis, in combination with a plurality of condenser plates received in said slits, the material between the slits being spread into tight engagement with said plates and relatively disposed to maintain the median planes of said plates substantially equidistant.

In witness whereof, I hereunto subscribe my name.

PETER G. JACOBSON.
